UNITED STATES PATENT OFFICE.

JOHN E. WRIGHT, OF NEW YORK, N. Y.

TELEGRAPH SYSTEM.

1,219,522.

Specification of Letters Patent. Patented Mar. 20, 1917.

Application filed January 15, 1916. Serial No. 72,821.

To all whom it may concern:

Be it known that I, JOHN E. WRIGHT, a citizen of the United States, residing at New York, in the county and State of New York, have invented certain new and useful Improvements in Telegraph Systems, of which the following is a full, clear, and exact description.

In systems for the transmission of electrical impulses over a line for the operation of telegraph instruments, the length of such line, or its character with regard to the impedance which it offers to the ready passage of impulses of either one or both polarities, often determines the amount and character of the work which it is capable of performing. When the inductive effects are of such a nature, for example, that any one or a succession of similar impulses sent into the line become blocked or perceptibly weakened, some means must be provided for clearing the line after each impulse or group of impulses in order to permit of working at practicable or commercial speeds, and many plans have heretofore been practised for this purpose.

The object of the improvement upon which is based the present application for patent, is to improve the character and carrying quality of the signal impulses of current sent over telegraph lines in general, and more particularly those in which the inductive capacity is such as to play an important part in the transmission of impulses, and in order to convey a clear understanding of the nature of the improvement we may assume the conditions met with in an ordinary case.

Let it be assumed, for example, that we are dealing with a system in which all impulses of current sent to line, originate from a suitable source and are directed through the segments of a commutator or sunflower instrument, to the relay which sends corresponding impulses over the line. In such cases it is usual to employ a relay designed to operate as a pole changer, through which all of such original impulses are sent and which operates to transmit over the line from the main battery positive or negative currents corresponding to the source or direction of those received from the sunflower

segments by the magnet of the pole changer. It is, for example, a common expedient to send out from that segment upon which the contact brush bears when at rest, a negative impulse or current and from the remaining segments, currents from the positive pole of the local battery.

The pole changer habitually used for this purpose is a polarized relay with an armature or tongue connected to line, and its front and back stops connected with the positive and negative poles of the source of line current respectively. In this arrangement when the pole changer is used, for instance, in connection with a printing telegraph instrument, the movements of the relay tongue controlled by the impulses proceeding from the commutator or sunflower segments, respond to the polarities of the impulses with which the segments may be charged, as the relay magnet receives them by the movement of the contact brush over such segments. If the first segment from which an impulse is received be positive, the tongue will take up a certain position and maintain it until a segment with a negative charge is encountered, the insulation between segments with corresponding interruptions of current having no effect upon the position of the tongue of the pole changer.

Thus, if the sunflower have eight segments which are alternately charged positive and negative, the tongue during one revolution of the contact brush, will make four movements in each direction. On the other hand, if all the segments are of the same polarity the tongue will not move at all, and practically only one impulse will be sent to line during one rotation of the brush, thus rendering the line liable to become blocked and offer a more or less pronounced opposition to the free passage of impulses.

This condition of things I propose to remedy, by the employment of a pole changer comprising two independent electromagnets, one normally in a circuit from all the segments of the commutator or sunflower, and the other in a circuit which is permanently connected with one, the starting segment, but adapted by the operation of the keys or

other transmission devices, to be connected through the selective magnets of the translator with such of the other segments as may be necessary for producing the desired combination of signal impulses. Each magnet has a pivoted circuit controlling armature adapted to send to line an impulse corresponding in direction to the particular selective magnet that may be operated, and each adapted on the cessation of any impulse through it, as by the passage of the rotating contact brush of the sunflower over insulation intermediate to the conducting segments, to connect the line with ground, whereby said line is cleared after each impulse without regard to its direction or that of preceding or succeeding impulses.

The details of this invention may perhaps be best explained by a description of the apparatus and its mode of use which I have shown in the accompanying sheet of drawings, which is a diagrammatic illustration of such parts of an ordinary composite system, or one designed for the conjoint use of telephones and Morse or similar instruments, as are necessary for an understanding of the nature and purpose of my special improvement.

In this diagram assume that A represents the development in a plane of the segments of a sunflower disk, in this particular instance eight in number. A' is a local battery grounded at one pole and connected at the other to a brush A'' which, we assume, is normally stationary, but adapted, when started, to sweep over the segments in regular succession. Normally, the brush rests on segment 1. From this it is started by the operation of any key of the transmitter, not shown in this drawing, and in its movement first encounters the segment 2, which is for starting the sunflowers and then passes over segments 3 which send to line the impulses making up the signal combinations.

The segment 1 is permanently connected by wire 4 with an ordinary relay magnet B, said wire being grounded. The relay B is provided with armature E, retracted by a spring G, and vibrating between stops H and K, and under the assumed conditions while the sunflower is at rest, the magnet B is energized and the armature E drawn up against the front stop H.

55 A second electro-magnet C is also used and connected by a wire 5 to ground on the one hand and to the parts or circuits of the transmitter operated according to the signals to be sent on the other. This magnet is similarly provided with an armature F and stops H and K.

The front stops H constitute the positive and negative terminals of a line battery L, grounded at its middle point M, and both

back stops K are adapted to be connected either to line or to ground according to the positions of the armatures E and F, conveniently, by connecting the armature E with the back stop of armature F, the back stop of armature E to ground, and armature F to line R.

The segment 2 is permanently connected through a starting magnet 6 to the magnet C and the remaining segments 3 are normally connected to the wire 4 by wires 7 75 and contacts W which normally rest upon the back stops 8 of circuit controllers operated by the keys or transmission devices of the instrument.

From this arrangement it follows that 80 the magnet B normally energized, sends from battery L a negative current to line, but when the sunflower is started, the first current impulse from segment 2 passes through the magnet 6 and wire 5 through 85 magnet C. By the same movement of the brush A' the circuit of magnet B is interrupted, and hence a positive impulse, succeeding the negative impulse, is sent to line by magnet C. 90

If none of the contact levers 8 are shifted by the transmitter mechanism, the further movement of the brush A' will result in sending six successive impulses of current through magnet B and six corresponding 95 negative impulses to line R, but, in this, and in all cases, it will be observed that the brush A' in passing from one segment to the next passes over insulation S and 100 interrupts the current flowing from the sunflower and hence deenergizes the magnet B or C or both, as the case may be, and this connects the line to ground after each interruption.

If, on the other hand, any one or more 105 of the contacts 8 be shifted, then when the brush A' reaches the segment thus connected through one of the selective magnets D with magnet C, a positive or signal impulse is sent to line by the last named magnet and then the line is grounded, as above explained.

For purposes of the present case, it is not necessary to go into a detailed description of the diagram beyond this point. The 115 latter represents, conventionally, an ordinary composite circuit which will be perfectly intelligible to those skilled in the art, and is typical of any other circuit with which the invention may be used. It will 120 be understood that in this, as in many of such systems, the only current impulses effective in operating the receiver are those from the positive pole of the line battery, and that the negative impulses are merely 125 for the purpose of clearing the line.

The diagram illustrates an arrangement of pole changer entirely different from that

ordinarily used, and the signals transmitted in the system shown take on a wholly different character. They are broken up by the interposition of a ground connection whenever the sunflower brush passes over the insulation spaces S between two adjacent segments, at which times, as is obvious, the armature tongues E, F will fall back upon the back stops or contacts K as the current of the relay magnets is then interrupted. By thus momentarily connecting the line to ground it will rid itself of the inductive charge caused by the preceding impulse.

From the above description and illustration it will be observed that if five or six impulses in the same direction be sent to line during one revolution of the contact brush, the line would be grounded between succeeding impulses, and would not, therefore, be surcharged by a prolonged wave of current in one direction as would be the case with ordinary pole changer transmission.

On a difficult circuit of high inductive capacity, the five or six impulses would probably reach the receiving end, under ordinary conditions, as one impulse, but a galvanometer or a milliammeter T in the transmission circuit of my system will not swing appreciably from zero, showing that the line is not being highly charged. The advantage of not overcharging the line is obvious. The path for every impulse is cleared by the connection to ground preceding and following such impulse and the signal reaches the receiving end through even telephone composite circuits, unblurred and well defined.

Another advantageous result secured by the use of this compound relay device is the virtual cutting of the battery potential in half. The positive and negative poles are widely separated and the tendency to sparking is greatly reduced, and, in fact, the use of a small condenser Y completely eliminates the spark.

Still another advantage derived from the arrangement, and a very important one, is that by its use the noise in the telephone V, when a composite circuit is used, is measurably reduced as compared with that made by signals from an ordinary pole changer under like conditions. This is probably due to the even charging and discharging of the line, the battery potential never rising much above the point reached by brush contact with one segment.

A compound relay of the general character described is not in itself a new device, but so far as I am aware, it has never been employed as I have here shown it, as a pole changer. I have discovered that its use on composite circuits of considerable length has been attended with the most unexpected results, the noise in the telephone, for example,

having been reduced as much as seventy-five per cent.

What I claim is:

1. In a telegraph system, the combination with a source of current and means for sending by its use impulses of either positive or negative current to line, of a compound relay comprising two electro-magnets with which the current sending devices are respectively connected or adapted to be connected, and circuit controlling devices actuated by the said two magnets for transmitting to line current impulses of opposite direction and grounding the line after each transmitted impulse.

2. In a telegraph system, a source of current and a commutator or sunflower, the segments of which are adapted to be successively charged thereby, in combination with a compound relay comprising two electro-magnets with which the said segments are connected or adapted to be connected, and circuit controlling means actuated by the said magnets for sending impulses of opposite direction to line and for connecting the said lines to ground after each interruption of current through either magnet, as set forth.

3. In a telegraph system, a source of current and a commutator or sunflower, the segments of which are adapted to be successively charged thereby, in combination with two electro-magnets and circuit connections between the same and the said segments, means for controlling said circuit connections, armatures for the magnets, a battery, the opposite poles of which are adapted to be connected to line by the movements of the armatures, and a connection between the line and ground adapted to be closed whenever the circuit through the magnets is interrupted.

4. In a composite telegraph system involving the use of transmitting and receiving telephone and current impulse operated mechanism, the combination with the transmission line of a source of current impulses, a compound relay comprising two magnets adapted to be energized by such current impulses and to send opposite flowing impulses over the line according to which magnet is energized, and means operated by such magnets to establish, after each impulse so sent, a connection between the line and the ground.

5. In a telegraph system, the combination with a transmitter and means therein for developing current impulses which produce in the line corresponding impulses, of a compound relay comprising two magnets, one adapted to connect the positive and the other the negative poles of a battery to line, means for connecting one or the other magnet in the circuit of the impulses developed by the transmitter, according to the nature

and purpose of such impulses, and means controlled by the magnets for grounding the line after each transmitted impulse.

6. In a telegraph system, the combination with transmitting mechanism comprising a sunflower or commutator, of a compound relay consisting of two neutral electro-magnets, circuit controllers operated thereby,

one for sending positive and the second negative currents to line, permanent connections 10 between one magnet and the sunflower segments, and means for connecting the second magnet with certain of the segments when signal impulses are to be transmitted.

In testimony whereof I affix my signature. 15
JOHN E. WRIGHT.
